The Procter & Gamble Company, Cincinnati, Ohio, a corporation of Ohio

Filed May 7, 1968, Ser. No. 11,815

Term of patent 14 years

Int. Cl. D9—01

U.S. Cl. D9—100

FIG. 1 is an elevational view of a bottle or similar article showing my new design;

FIG. 2 is a fragmentary elevational view thereof, on a greatly enlarged scale, of the ribbing around the shoulder;

FIG. 3 is a fragmentary elevational view thereof, on a similarly enlarged scale, of the ribbing near the bottom;

FIG. 4 is a top plan view thereof; and

FIG. 5 is a fragmentary cross sectional view thereof taken on the line 5—5 of FIG. 1.

The side opposite that seen in FIG. 1 is the same in appearance as the side shown.

I claim:

The ornamental design for a bottle or similar article, as shown and described.
